George Jones Inventor
Attest,

UNITED STATES PATENT OFFICE.

GEORGE JONES, OF PEEKSKILL, NEW YORK.

IMPROVED DEVICE FOR TIGHTENING WINDOW-SASHES.

Specification forming part of Letters Patent No. 37,346, dated January 6, 1863.

To all whom it may concern:

Be it known that I, GEORGE JONES, of Peekskill, in the county of Westchester and State of New York, have invented a new and improved device for tightening window-sashes in their frames to prevent them from rattling; and I do hereby declare that the following is a full, clear, and exact description of the same, reference being had to the accompanying drawings, making a part of this specification, in which—

Figure 1 is a front or face view of a window having my invention applied to its lower sash; Fig. 2, a vertical section of the same, taken in the line xx , Fig. 1; Fig. 3, a detached perspective view of my invention.

Similar letters of reference indicate corresponding parts in the several figures.

The object of this invention is to obtain a simple device for tightening or securing window-sashes in their frames in such a manner as to effectually prevent them from rattling under the action of the wind, and thereby obviate the use of temporary wedges and sundry articles when procurable, being inserted between the sash and the side strip of the frame to effect the result. Proper articles for this purpose are not always at hand, and the occupant of a bed-room is in consequence frequently disturbed of his rest on account of the rattling of the sashes.

My invention is designed for a permanent fixture, may be obtained and applied at a small cost, and adjusted in a moment of time, so as to accomplish the desired end.

To enable those skilled in the art to fully understand and construct my invention, I will proceed to describe it.

A represents a window-frame, and B B' the sashes fitted within it in the usual manner.

C C represent two angle-shaped pieces of metal, the arms a of which are screwed firmly to the sides of the window-frame at right angles with the front or face side of the lower sash, B. The other arms, b , of the angle-pieces are consequently parallel with the front

or face sides of the sash B, and a short distance in front of it.

Through the arms b of the angle-pieces thumb-screws D pass, one through each. These screws are directly in front of the side pieces, $c c$, of the sash B, and to said side pieces, in line with the thumb-screws, there are secured metal plates d d, one for each thumb-screw, to serve as bearing-plates for the ends of the screws and prevent any indentation or abrasion of the sash.

From the above description it will be seen that by turning the thumb-screws D in the proper direction the upper and lower rails, $a' a''$, sash B, will be pressed back in close contact, respectively, with the upper sash, B', and the parting-bead e of the window-frame, and, consequently, the sash will be effectually prevented from rattling under the action of the wind. When it is necessary to raise the sash, the thumb-screws D are screwed outward, so as to be free from it.

If desired, the bearing-plates d d may be indented so as to receive the ends of the thumb-screws when the latter are screwed up in contact with them, and thereby serve as a fastening to secure the sash in a closed state.

The angle-pieces may be of malleable cast-iron, brass, or white-metal, and may be manufactured at a small cost including the screws D.

The device, if desired, may be applied to the upper as well as to the lower sash of a window.

Having thus fully described my invention, what I claim as new, and desire to secure by Letters Patent, is—

The combination of the angle-pieces C C, thumb-screws D D, and bearing-plates d d, applied, respectively, to the window frame and sash, substantially as and for the purpose herein set forth.

GEO. JONES.
